William L. Bower, Sheffield, England, assignor to James Neill & Company (Sheffield) Limited, Sheffield, England

Application February 27, 1959, Serial No. 54,768

Claims priority, application Great Britain
October 24, 1958

Term of patent 14 years

(Cl. D93—4)

FIG. 1.

FIG. 2.

FIG. 3.

FIG. 4.

FIG. 5.

FIG. 6.

FIG. 7

FIG. 8.

Figure 1 is an elevational view of one side of a handle unit for adjustable hand saw embodying my new design;

Figure 2 is an end view taken from the right of Figure 1;

Figure 3 is an elevational view of the opposite side of Figure 1;

Figure 4 is an elevational view of the opposite end of Figure 2;

Figure 5 is a top plan view of Figure 1;

Figure 6 is a section on line C—C of Figure 1;

Figure 7 is a section on line D—D of Figure 3; and

Figure 8 is a perspective view from the left and from the bottom of Figure 1.

I claim:

The ornamental design for a handle for an adjustable hand saw, as shown.
